UNITED STATES PATENT OFFICE.

FREDERICK J. MADELL, OF NEWARK, NEW JERSEY, ASSIGNOR, BY MESNE ASSIGNMENTS, TO CHARLES H. STREIT, OF NUTLEY, NEW JERSEY.

CLASP.

1,291,052.

Specification of Letters Patent. Patented Jan. 14, 1919.

Application filed June 18, 1913. Serial No. 774,383.

To all whom it may concern:

Be it known that I, FREDERICK J. MADELL, a subject of the King of England, and a resident of the city of Newark, county of 5 Essex, and State of New Jersey, have invented certain new and useful Improvements in Clasps, of which the following is a specification.

This invention relates to an improved 10 clasp which can be used for clasping the ends of bands or strands of a flexible or semi-flexible nature, and is designed to hold material between the back plate and the lever, the elements to be forced against 15 the back plate being caused to assume a sinuous formation or path so that they are frictionally held against longitudinal movement through the clasp. The clasp while adapted for general use, is also applicable 20 to a particular purpose which is the holding or fastening of bands made of metal, such as thin steel bands which are smooth and slippery on their surfaces, and I have found that considerable pressure is necessary, in 25 the ordinary clasp, for holding the bands against slipping. The lever is also designed to provide a clearance so that the clasp, when supported on supporting strips, clears 30 said strips, as will be hereinafter described.

30 The particular use of the clasp is in conjunction with dress forms, a sample of which is shown in Patent No. 991,241, and also in the kind of dress form shown in my application filed June 20, 1912, Serial No. 704, 35 721. In dress forms of this kind tapes surround the form at certain heights, such as at the bust, waist, hips and so forth, and these bands, when adjusted, are held by clasps.

40 The old style of clasp, such as shown in Patent No. 991,241 does not indicate, except to the touch, when it is secure. In other words, in the many adjustments necessary in changing the dress form, it is very likely that the dressmaker will over- 45 look the fastening of one of the many clasps on the form, and when the form is to be used, pressure, when applied to such parts, causes a sliding of the tape through the clasp, and in this way the form is disar- 50 ranged and partly collapsed or extended and adjustment must begin all over again and measurements taken to insure the proper dimensions of the dress form.

In my improved clasp the handle pro- 55 jects when the clasp is open so that the

projecting handles interfere with the placing or fitting of material on the dress form, thus insuring their observation by the dressmaker who presses the handle to its locked position so as to get it out of the way. In 60 the dress forms above mentioned, toggles and sliding clips are employed to hold contour wires, but these have not been illustrated in this drawing, except to show in dotted outline several contour wires which 65 pass through the plate of the clasp.

The invention is illustrated in the accompanying drawing, in which Figure 1 is a top view of my improved clasp. Fig. 2 is a face view of the clasp shown in Fig. 1, 70 and Fig. 3 is a perspective view of the lever employed in the clasp.

The illustration shows one end 10 of a strand which, in the dress form, is made of steel and is smooth and slippery and 75 which will not be held by an ordinary clasp, this end of the strand 10 being called a fixed strand end for the purpose of this specification, and the end 11 being the loose strand end which is the element that is 80 compressed between the lever and the back plate of the clasp, although more than a single strand can be compressed in the clasp. The clasp consists of a back plate 12 having spaced projections 13 projecting therefrom, the projections in the form embodied in the illustration consisting of the heads of rivets, which rivets are used to fasten the strand or tape 10 to the back plate of 85 the clasp.

Projecting from the top and bottom edges of the back plate and in the spaces between the projections 13 are the ears 14. The lever which operates between the ears consists of an arm 15, the end 16 of which is adapted to 90 be pressed to engage an element to be clasped or squeezed against the back plate. The arm is merged at its top edge into the angular portion 17 which is arranged at an acute angle to the arm and extends into a handle 18, the juncture of the angular portion 17 and the handle 18 forming a nose 19, the end 20 of the handle being turned outward to form a finger-piece to provide for the ready engagement of the handle by the finger when the handle is to be unlocked. The lever is fixed between the ears so that it swings therein on the pivotal pin 21, the preferred form of arm to embrace the pivotal pin being illustrated in the drawing, the arm 100 105 110

being forced outward in a central loop 22 and flanking loops 23, the loops being projected or forced from opposite sides of the arm so that they form an eye or duct 24 which extends through them and between them, furnishing a passage for the pin 21. The arm and the nose are so disposed that when they are in position, the nose engages the element to be clasped, in the illustration 10 this being the strand 11, and forces it down between the projections 13 whereby it is bent to make it sinuous, and this is carried out further by the location of the nose 19 which engages the strand 11 beyond one of the projections 13 and submits it to another bending whereby two positive points of engagement are provided, and both points cause a bending of the clasped element, such as the strand 11.

15 In dress forms of the kind described the clasp is arranged to be slid along certain contour wires which are not shown, except for two illustrated in dotted outline at 25 in Fig. 2, which contour wires extend through the perforations 26 in the ears 14. The handle with its curved portion and the angular portion 17 establishes a recessed part of the lever which permits the lever to be swung to an open position or far enough toward an 25 open position to permit the release of the strand 11 and still clear the contour wires 25, and when so projected the handle is in the way of any fitting on the dress form, and thus guards against accidental release of the 30 form until the clasps are shut, the clasps, by their projecting handles, calling attention to the fact that they are still open. This location of the handle in rear of the contour wires gives a free and smooth contour when 35 40 the handle is shut, but does not in any way interfere with the swinging of the handle of the clasp.

In the drawing it will be noted that I have illustrated the clasp in Fig. 1 as being substantially in locked position, but in practice 45 the parts are disposed so that the end 16 of the arm of the lever passes beyond the center of the pivot to positively lock the clasp in position and thus give greater strength and security. 50

Having thus described my invention, what I claim is:—

A clasp consisting of a substantially flat back plate having rivets with heads projecting from the plate and spaced apart, a lever pivoted to said back plate, said lever having a nose arranged substantially radially in respect to its pivot, the lever also having an angular portion substantially tangential to its pivot, the nose and the angular portion being spaced so that when in locking position the nose is substantially perpendicular to the back plate and is adapted to press a tape in the clasp substantially squarely against the face of the back plate between 65 the rivet heads while the angular portion bears against the tape beyond one of the rivets whereby the tape is forced into a sinuous formation, a handle on said lever projecting beyond the angular portion and spaced away from said tape when the junction of the angular portion and the nose are in contact with the tape, whereby the handle may be readily grasped when the lever is in locking position, and means whereby the 70 75 clasp may be mounted for lateral sliding movement on contour wires.

In testimony that I claim the foregoing, I have hereunto set my hand, this 17th day of June, 1913.

FREDERICK J. MADELL.
